INK BOTTLE

Fabius M. Butler, Seattle, Wash.

Application January 19, 1935, Serial No. 2,561

1 Claim. (Cl. 120—69)

This invention relates to ink or measuring bottles, and it has reference more particularly to improvements in bottles whereby provision is made for the filling of fountain pens therefrom.

Explanatory to the invention, it will here be stated that in filling a fountain pen from the ordinary type of bottle, it is required that the pen be extended down into the bottle through the restricted neck portion. As a general rule, the pen is rested against the bottom of the bottle. If the bottle contains a substantial quantity of ink, the pen is invariably smeared along the sides and over the end, due to its projection into the bottle. If the bottle contains little ink, then the point is not properly covered to insure filling by suction.

To overcome this disadvantage, certain improvements have heretofore been made, such for instance as the patent to H. Smith, No. 1,308,817 of July 8, 1919, wherein an insert is applied to the bottle and this is equipped with a cup having a valved base opening through which the cup will be filled on inverting the bottle, but which will automatically close when the bottle is turned to upright position, thereby to trap sufficient ink for filling a pen therefrom. While the device of Smith is satisfactory to a certain extent, it is relatively expensive and occupies a considerable amount of space in the bottle.

Another form of device is shown in U. S. patent to C. W. Dennis, et al. No. 1,966,754 of July 17, 1934, consisting of a cup member inserted within the neck portion of the bottle, which principle is much like that of Smith, above referred to, and having the undesirable feature of being an extra inserted element of a comparatively expensive nature and not entirely satisfactory from the standpoint of ink holding.

In view of the undesirable features of bottles of this type heretofore employed, it has been the principal object of this invention, to provide an improved form of bottle wherein the neck portion provides a pen filling cup and this is connected to the bottle by means of a restricted neck portion forming a seat for a valve member of novel form which operates automatically to admit ink to the cup when the bottle is inverted and will seat and retain the ink in the cup when it is turned to upright position.

It is also an object of the invention to provide a novel form of valve member which operates not only as the valve but is so shaped as to serve, as a rest for the pen in filling and also as an air trap when the bottle is inverted for filling the cup.

Another object of the invention is to provide a construction that is less expensive than those previously used, by reason of converting the bottle neck portion into a filling cup as distinguished from the use of inserted elements for the purpose.

Other objects of the invention reside in the details of construction of the various parts, in their relationship and mode of operation as will hereinafter be described.

In accomplishing these and other objects of the invention, I have provided the improved details of construction, the preferred forms of which are illustrated in the accompanying drawing, wherein—

Fig. 1 is a cross sectional view of an ink bottle constructed in accordance with the present invention, in normal position.

Fig. 2 is a view in cross section illustrating the filling of the neck portion with ink by inversion of the bottle.

Fig. 3 is a cross sectional view illustrating the filling of a pen with ink trapped in the cup incident to turning the bottle to upright position after being inverted as in Fig. 2.

Fig. 4 is a sectional detail of an alternative form of construction.

Referring more in detail to the drawing—

1 designates in its entirety, an ink bottle which may be of any suitable or convenient size for a substantial supply of ink and provided at the top with an extended, integral neck portion 2 over which a cap 3 is removably threaded. The neck portion, in this particular instance forms the pen filling cup 4 and this communicates with the interior of the bottle proper through a neck passage 5 of a restricted diameter. The base or bottom of the cup 4 is conically tapered downwardly to the central passage 5 and preferably would have a smoothly ground surface to provide for accurately seating a valve member that is applied thereto.

The valve member comprises a semi-cylindrical head 6 from which a downwardly directed stem 7 extends; the stem being extended in a direction radial of the semi-cylindrical surface. The head 6 is adapted to seat in a liquid tight joint or seal against the upper peripheral edge of the passage connecting the cup and bottle and the stem is extended through the communicating passage 5 and is sufficient in length that it will keep the valve member in proper relationship with its coacting parts whether inverted or upright.

The cap 3 of the bottle is provided on its under surface with a downwardly rounded protuberance

3a extended into the cup, and this occupies a certain amount of space that prevents the cup being filled clear to the top, but will hold the level slightly below the top periphery and thereby insure against overflow on insertion of a pen thereinto.

5 The top surface of the valve head is formed flat, with a concentric downwardly tapered conical basin 9. This basin, as will be observed by reference to Fig. 2, serves as an air trap when the cup is inverted and supplements the protuberance, of the cap in preventing the entire filling of the cup when the bottle is inverted. This basin also serves as a centering guide for the pen where it is inserted for filling.

10 15 Assuming the bottle to be so constructed, it is used as follows: With the cap threaded tightly onto the bottle neck, and with the parts in position, as shown in Fig. 1, the bottle is inverted to cause the valve member to drop, as shown in Fig. 2, against the cap and permit filling of the neck portion with ink. Then the bottle is quickly turned back to upright position, thereby causing the valve to drop back to closed position, thus to trap the ink within the cup, by the seating of the valve member.

20 25 The cap of the bottle is then removed and the pen 10 to be filled is inserted, as shown in Fig. 3, with the pen point resting within the vertex of the conical recess on basin 9 in the valve member; it being understood that the taper of the basin guides the pen point to this central location and whatever pressure there is then applied against the valve will not cause it to tilt and unseat. With the pen thus inserted it may be filled in the usual way.

30 35 It is to be observed in this construction that the bottle neck itself provides the filling cup. Its restricted neck passage provides the valve seat

and there is no complicated or expensive insert applied to the neck or bottle. The only added part is the valve member and this, it is intended, shall be cast or pressed from a relatively inexpensive material of any suitable kind.

5 The construction has the advantage of being inexpensive; it is practical; satisfactory in use and prevents smearing the pen with ink during a filling operation.

10 Such bottles may be made in various sizes and in various proportions according to any requirement and it is to be understood that the depth and width of the filling cup can be varied to suit any special condition or requirement. Fig. 4 illustrates a construction in which the bottle neck 15 is enlarged to provide a reservoir of considerable capacity.

20 Having thus described my invention, what I claim as new therein and desire to secure by Letters Patent is—

An ink bottle having an integral neck portion forming a pen filling cup of substantial volume and of a depth sufficient to receive a suction filled pen of the fountain type to the extent required for filling, a closure cap for the cup; said neck being formed with a restricted passage into the bottle through which the cup is filled incident to inversion of the bottle; and said passage being formed with a valve seat, and a valve contained within the neck portion to open when the bottle is inverted and to close against the seat when the bottle is returned to upright position, and provided in its top surface with a conical depression forming an air trap chamber when the bottle is inverted, and forming a pen point rest 30 during a pen filling operation.
